UNITED STATES PATENT OFFICE.

HERMAN BURCHESS, OF CHICAGO, ILLINOIS, ASSIGNOR OF ONE-HALF TO ELIAS ROSS,
OF NEW YORK, N. Y.

HINGE.

1,092,136.

Specification of Letters Patent.

Patented Apr. 7, 1914.

Application filed October 20, 1913. Serial No. 796,211.

To all whom it may concern:

Be it known that I, HERMAN BURCHESS, a citizen of the United States, and a resident of the city of Chicago, county of Cook, and 5 State of Illinois, have invented certain new and useful Improvements in Hinges, of which the following is a specification.

My invention relates to hinges and more particularly to a hinge adapted for use especially upon suit cases.

The object of my invention is the production of a hinge as mentioned which, when in use will permit of the cover of the suit case being swung to entirely open position or 15 which, may be adjusted, to limit the opening movement of the cover so as to support the same in substantially vertical position.

A further object is the production of a hinge which will be of durable and economical construction and efficient in use.

Other objects will appear hereinafter.

The invention consists in the combinations and arrangements of parts hereinafter described and claimed.

25 The invention will be best understood by reference to the accompanying drawing forming a part of this specification, and in which,

Figure 1 is a vertical transverse section of 30 a suit case equipped with a hinge embodying my invention, Fig. 2 is a perspective view of the hinge detached, Figs. 3 and 4 are perspective views of the component parts of the hinge disconnected.

35 The preferred form of construction as illustrated in the drawing comprises a leaf 1 provided at one edge with a pintle 2 secured to said edge by means of ears 3 and 3' which project from the terminals of said 40 edge, the outer ends of said ears being preferably formed integral with said pintle as illustrated. Coöoperating with the leaf 1 is a second leaf 4 formed at one edge with an outwardly looped portion 5 which constitutes a bearing for the pintle 2 which is 45 adapted to snugly engage said portion 5, as clearly shown in Fig. 2. Also formed upon the leaf 4 are shoulders 6 adapted for engagement with the ears 3 and 3' of leaf 1 to 50 constitute a stop therefor and limit the amplitude of swinging which is permitted said leaf as will be readily understood. The ears 3 and 3' however are separated a distance greater than the width of the bearing portion 5 of leaf 4 so as to permit of shifting

of the leaf 1 relative to leaf 4. This being so if it is desired to permit of entire freedom of movement of leaf 1 it is only necessary to shift the latter until the ear 3 thereof registers with a slot or notch 7 cut in the 60 corresponding shoulder 6 and until the ear 3 is out of registration with the other of said shoulders, when the amplitude of swinging movement permitted said leaf 1 will be increased so as to permit of the same swinging 65 to the dotted line position shown in Fig. 2.

In order to reinforce the bearing loop 5 of leaf 4 the former is provided with an extension 8 which is perforated so as to permit of the same being rigidly secured to the adjacent wall of the suit case or other device in conjunction with which the hinge is employed. Through the provision of the extension 8 it is evident that the loop 5 will be 70 materially reinforced or strengthened so as 75 to be adapted to withstand the severe strains to which the same is subjected in use.

At the rearward or inner side of the leaf 4 is arranged a rubbing plate 9 which is adapted to contact with the inner side of 80 pintle 2 so as to protect the adjacent wall of the suit case which otherwise would be worn through engagement therewith of said pintle in rotating. Through the provision of plate 9 injury to the adjacent wall of the 85 suit case through contact therewith of the pintle of the hinge will be obviated, this rubbing or wearing of the pintle upon the suit case wall being one of the objections to hinges of this character in use at the present 90 time.

In using the hinge the leaf 4 together with the plate 9 is secured as by riveting to the body 10 of the suit case adjacent the upper edge thereof, the extension 8 being secured 95 to the angularly disposed flange 11 provided at said edge of the suit case body as shown in Fig. 1. The leaf 1 is secured as by riveting to the cover 12 of the suit case. When the leaves 1 and 4 are in the relative positions shown in full lines in Fig. 2 the suit case cover will be limited in its opening movement, the same being permitted to swing only to its vertical position as shown in dotted lines in Fig. 1, in which position 100 the same will be supported by reason of the shoulders 6 on leaf 4 which will be engaged by the ears 3 and 3' on leaf 1. When it is desired to entirely open the suit case cover it 105 is only necessary to shift the same laterally 110

until the ear 3 registers with slot or notch 7, in which event the cover will be released so as to swing to its entirely open position as also shown in dotted lines in Fig. 1.

5 While I have illustrated and described the preferred form of construction for carrying my invention into effect, this is capable of variation and modification without departing from the spirit of the invention. I, 10 therefore, do not wish to be limited to the precise details of construction set forth, but desire to avail myself of such variations and modifications as come within the scope of the appended claims.

15 Having described my invention what I claim as new and desire to secure by Letters Patent is:

1. A hinge comprising a leaf having a pintle; a second leaf having an outwardly 20 looped portion constituting a bearing for said pintle; and a shoulder on said second mentioned leaf adapted for engagement by said first mentioned leaf to limit swinging of the latter in one direction, said first mentioned leaf being adapted to be shifted to disengage 25 said shoulder and permit of a greater amplitude of swinging of said leaf, substantially as described.

2. A hinge comprising a leaf having a 30 pintle; a second leaf having an outwardly looped portion constituting a bearing for said pintle; and a shoulder on said second mentioned leaf adapted for engagement by said first mentioned leaf to permit swinging 35 of the latter in one direction, a portion of said second mentioned leaf being cut away and said first mentioned leaf being adapted to be shifted to register with said cut away portion and disengage said shoulder to permit 40 of a greater amplitude of swinging of said leaf, substantially as described.

3. A hinge comprising a leaf having a 45 pintle provided at one edge thereof and supported by two ears projecting from said edge; a second leaf having an outwardly looped portion constituting a bearing for

said pintle; and a shoulder on said second mentioned leaf adapted for engagement by said supporting ears of said first mentioned leaf to limit swinging of the latter in one 50 direction, a portion of said shoulder being cut away and said first mentioned leaf being adapted to be shifted to move said ears from engagement with said shoulder and into registration with said cut away portion to 55 permit of a greater amplitude of swinging of said leaf, substantially as described.

4. A hinge comprising a leaf having a pintle; a second leaf having an outwardly 60 looped portion constituting a bearing for said pintle; a shoulder on said second mentioned leaf adapted for engagement by said first mentioned leaf to limit swinging of the latter in one direction, said first mentioned leaf being adapted to be shifted to disengage 65 said shoulder and permit of a greater amplitude of swinging of said leaf; and a reinforcing extension on said second mentioned leaf formed for fastening in position, substantially as described.

70 5. A hinge comprising a leaf having a pintle; a second leaf having an outwardly looped portion constituting a bearing for said pintle; a shoulder on said second mentioned leaf adapted for engagement by said first mentioned leaf to limit swinging of the latter in one direction, said first mentioned leaf being adapted to be shifted to disengage 75 said shoulder and permit of a greater amplitude of swinging of said leaf; and a rubbing plate provided at the inner side of said second mentioned leaf for contact with the inner side of said pintle, substantially as described.

In testimony whereof I have signed my 80 name to this specification in the presence of two subscribing witnesses.

HERMAN BURCHESS.
